UNITED STATES PATENT OFFICE.

LUIGI ZOPPI, OF NICASIO, CALIFORNIA.

ELECTRIC CLOCK.

Application filed May 26, 1924. Serial No. 715,790.

This invention relates generally to clocks, having more particular reference to a novel form of electrically operated clock which is controlled by a master clock.

5 The invention has for an object to provide a novel and simple form of electrically controlled clock in which the hands may be given a substantially continuous movement simulating the movement of a clock driven 10 by the usual clock mechanism.

For further comprehension of the invention, and of the objects and advantages thereof, reference will be had to the following description and accompanying drawing, 15 and to the appended claims in which the various novel features of the invention are more particularly set forth.

Fig. 1 of the drawing is a vertical sectional view showing the mechanism of my 20 improved clock, this view being taken generally along the line 1—1 of Fig. 2.

Fig. 2 is a horizontal sectional view taken on the line 2—2 of Fig. 1 and showing also the clock casing.

25 Fig. 3 is a detail vertical sectional view taken on the line 3—3 of Fig. 2.

Fig. 4 is a fragmentary horizontal sectional view taken at the point indicated by the line 4—4 on Fig. 3.

30 Fig. 5 is a detail sectional view of the clock device regulator.

Referring now to the drawing, a pair of vertical skeleton frame plates 10 are provided and are shown as united by posts 11 and may be secured at their lower ends in any suitable manner as for instance by screws 11' or the like, on the base of the 35 clock casing, which casing is indicated at 12. Fixed at one end to one of these frame members is a bearing sleeve 14 on which is mounted an oscillatory arm 15 which extends vertically at a point midway between the two frame elements and is pivoted on the sleeve between its ends. Extending freely through 40 this sleeve 14 is a shaft or arbor 16 which has the minute hand 17 mounted on its front end, this arbor extending also through the hollow arbor 18 of the hour hand 19, this hollow arbor being supported by a suitable bearing element 20 on the front 12' of the 45 casing 12, or in any suitable manner.

50 Fixed to the end of the arbor 16, remote from the minute hand 17, is the ratchet wheel 25 which is operatively engageable with pawl 27 carried by the arm 15 adjacent its upper end. Integral with the back

of hollow arbor 18 is the internal gear 36 which is engaged by an idler pinion 37 having a bearing in the frame 10 indicated at 50, and said pinion 37 meshes in turn with a small pinion 38 integral with ratchet wheel 26 having oppositely facing teeth to those of ratchet wheel 25, and 26 is operatively engageable with pawl 28 carried by the arm 15 near its upper end. The ratchet wheel 25 55 is rigidly fixed to arbor 16 which also has fixed thereto the minute hand 17, and the ratchet wheel 25 and pawl 27 are so arranged to turn the hand 17 clockwise when arm 15 oscillates. The ratchet wheel 26 60 is revolvable on arbor 16 and supported rotatably in frame 10, and said ratchet wheel 26 has the same size pawl action as ratchet wheel 25 so that when arm 15 oscillates each 65 wheel turns at the same speed. The wheel 26 is caused to turn anti-clockwise by the action of pawl 28, and having pinion 38 integral thereto which in turn meshes with idler 37, turns this said idler clockwise, and the idler meshing internally with gear 36 70 turns this gear also clockwise, while the hour hand 19 is fixed to the latter mentioned gear 75 75

20 and having pinion 38 integral thereto which in turn meshes with idler 37, turns this said idler clockwise, and the idler meshing internally with gear 36 80 turns this gear also clockwise, while the hour hand 19 is fixed to the latter mentioned gear 85

25 and having pinion 38 integral thereto which in turn meshes with idler 37, turns this said idler clockwise, and the idler meshing internally with gear 36 90 turns this gear also clockwise, while the hour hand 19 is fixed to the latter mentioned gear 95

30 and having pinion 38 integral thereto which in turn meshes with idler 37, turns this said idler clockwise, and the idler meshing internally with gear 36 100 turns this gear also clockwise, while the hour hand 19 is fixed to the latter mentioned gear 105

35 and having pinion 38 integral thereto which in turn meshes with idler 37, turns this said idler clockwise, and the idler meshing internally with gear 36 110 turns this gear also clockwise, while the hour hand 19 is fixed to the latter mentioned gear 115

40 and having pinion 38 integral thereto which in turn meshes with idler 37, turns this said idler clockwise, and the idler meshing internally with gear 36 120 turns this gear also clockwise, while the hour hand 19 is fixed to the latter mentioned gear 125

To regulate the oscillatory movement of the arm 15 so that the same will be relatively even I connect the arm to a retarding device which is mounted on the frame 10 and which consists of a short cylinder 40 divided midway between its ends by a partition 41, and having its ends closed by the corrugated steel diaphragms 42 each of which has a minute air-hole 43 therein. The end 10 of the arm is here shown as in the form of a pendulum-like housing or casing which straddles the cylinder 40 and has fixed in opposite sides thereof the studs 44, each of which is connected to one of the diaphragms 15 so that movement of the arm is regulated by the flow of air through the holes 43.

Having thus described my invention, what I claim as new and desire to protect by Letters Patent of the United States is as follows:

- 20 1. In an electrically controlled clock, hour and minute hands, a pair of electromagnets, and means through which the said electromagnets are caused to operate the respective hour and minute hands, including a pair of opposed ratchet wheels, an oscillatory arm having the armatures of the said magnets mounted thereon, a pair of pawls on said arm engaging the respective ratchet 25 wheels, and operative connections between the said ratchet wheels and the said hands.
- 25 2. In an electrically operated clock, hour and minute hands, arbors to which the respective hands are fixed, a pair of ratchet 30 wheels having oppositely facing teeth, one of said ratchet wheels being fixed on the arbor of the minute hand, an oscillatory arm having a pair of magnet armatures mounted thereon, a pair of electromagnets adapted 35 when energized to swing the said arm in re-

spectively opposite directions, and reducing gear connections between the other of said ratchet wheels and the arbor of the hour hand.

3. In an electrically operated clock, hour 45 and minute hands, arbors to which the respective hands are fixed, a pair of ratchet wheels having oppositely facing teeth, one of said ratchet wheels being fixed on the arbor of the minute hand, an oscillatory 50 arm having a pair of magnet armatures mounted thereon, a pair of electromagnets adapted when energized to swing the said arm in respectively opposite directions, and reducing gear connections between the other 55 of said ratchet wheels and the arbor of the hour hand, said reducing gear connections comprising a pinion fixed to the said ratchet wheel, an internal gear fixed to the said arbor, and an idler meshing with both said 60 gear and said pinion.

4. In an electrically operated clock, hour and minute hands, arbors to which the respective hands are fixed, a pair of ratchet 65 wheels having oppositely facing teeth, one of said ratchet wheels being fixed on the arbor of the minute hand, an oscillatory arm having a pair of magnet armatures mounted thereon, a pair of electromagnets adapted when energized to swing the said arm in 70 respectively opposite directions, and reducing gear connections between the other of said ratchet wheels and the arbor of the hour hand, and a double acting retardation device applied to said arm to regulate the 75 speed of movement thereof under the influence of said magnets.

In testimony whereof I have affixed my signature.

LUIGI ZOPPI.
